CLOTHESLINE SUPPORTING DEVICE

Alexander Nagy, Lindenhurst, N. Y.

Application June 8, 1944, Serial No. 539,300

3 Claims. (Cl. 211—119.07)

1

This invention relates to clothes line supporting devices in general, and more especially to a supporting device attachable to a house adjacent to a window, door, or the like to support a clothes line that extends from the house to an exterior support or the like.

Among the objects of the present invention it is aimed to provide an improved clothes line supporting device attachable to a house adjacent to an opening such as a window, door or the like, to facilitate hanging and removing clothes from the line without endangering the person of the attendant.

With a clothes line mounted upon pulleys attached to a house, particularly when the attendant is required to gain access to the line through a window, the person of the attendant has frequently been injured due to the breaking of the line while the attendant was engaging the same.

One of the objects of the present invention is to provide an improved clothes line attachment connected to a house adjacent to a window, door, or the like by means of which the attendant can with ease hang and remove the clothes on the line without requiring her to reach out of the house through the window, door, or the like.

Still another object of the present invention is to provide an improved clothes line supporting device connected to a house adjacent to a window, door, or the like, having a pulley supporting arm which may with facility be positioned to extend into the house while the clothes are being hung or removed from the line, and which in turn may be positioned to extend on the outside of the house to enable closing the window, door, or the like, and which in addition can be operated both when the clothes are hung on the line as well as when the line is free.

These and other features, capabilities and advantages of the invention will appear from the subjoined detail description of one specific embodiment thereof illustrated in the accompanying drawings, in which:

Figure 1 is a side elevation of a clothes line and the improved supporting device in position for hanging and removing clothes with a part of the supporting house shown in section.

Fig. 2 is a section on the line 2—2 of Figure 1.

Fig. 3 is an enlarged fragmental section in plan showing the supporting device extending into a house.

Fig. 4 is an enlarged fragmental section showing the supporting device secured to the outer face of a house.

2

Fig. 5 is a fragmental section on the line 5—5 of Fig. 3.

Fig. 6 is a section on the line 6—6 of Fig. 5.

Figs. 7 and 8 are sectional fragmental views of the latch in on end off positions.

In the embodiment shown the clothes line 1, secured to form an endless loop, extends around one pulley 2 attached to a hook 3 or the like, secured to any suitable exterior support such as the pole 4. The line 1 also extends around the pulley 5 which is secured to the hook or claw 6 of the arm 7 constituting a part of the supporting device 8 now to be described.

The supporting device 8 is intended to be attached to the outer face of a structure 9 such as a house adjacent to an opening in the structure, such as a doorway, window opening, or the like. In the present instance, the device 8 is shown as attached to the structure 9 adjacent the sash frame 10 of a window having slideways for two complementary window sashes 11 and 12. In Figure 1 the two window sashes 11 and 12 are raised to clear the arm 7 of the supporting device while it extends into the house. The arm 7 in the present instance is shown as composed of a metal rod having the hook or claw 6 at one end to receive the ear 13 of the pulley 5 and being at its other end welded into the plate 14. The plate 14 as shown has a slot therein to receive the rod 7 with the edges of the main portion 15 inclining toward one another as they extend toward the free end of the plate portion 15. The plate 14 in turn is bent to form an angle of about 86° between the main portion or web 15 of the plate 14 and the narrow portion or web 16. The free end of the narrow portion 16 has the loops 17 and 18 in alignment with the loop 19 formed at the free end of the plate 20 in turn to form a journal for the hinge pin 21. This pin 21 has a guiding claw or hook 22 formed at the lower end thereof and extending down below the plate 14, that is, below the loop 18 of the plate 14. The upper end of the pin 21 is preferably threaded to receive the nut 23 and above it the internally threaded element 24 has the guiding claw or hook 25 extending upwardly therefrom. The pin 21 is formed to rotate freely in the journals formed by the sleeves 17, 18 and 19 so that the hooks 25 and 22 may swing around the same with the upper and lower strands 26 and 27 of the line 1.

The plate 20 as shown preferably is bent at right angles having the web 28 provided with screw openings to receive screws such as the screws 29 which extend into the house, in the present instance being shown as secured to the

sash frame 10. The plates 14 and 20 may be composed of any suitable durable metal. Excellent results have been achieved when the metal of these two plates was composed of chrome molybdenum. Obviously the hinge pin 21, hook element 24 and hook element 6 and bar 7 are preferably composed of some durable metal. Excellent results have been achieved when these portions are composed of cold rolled steel. While the bar 7 and hook portion 6 may 10 be composed of one piece, preferably they consist of two pieces, the bar 7 then preferably being composed of a chrome molybdenum tube receiving a diminished portion of the hook portion 6, see particularly Fig. 3, composed of a cold 15 rolled steel.

While the dimensions and conformations of these several parts so far described may be varied without departing from the general spirit of the invention, it should be noted that excellent results have been achieved when the portion 15 of the metal plate 14 is about five and one-quarter inches long and one and one-half inches wide at its widest end adjacent the narrow portion 16; the narrow portion 16 about one and one-half inches long; the main portion of the plate 20 about two inches long by four inches wide; and the web 28 about one and one-half inches long; both plates 14 and 20 being about one-eighth of an inch in thickness; the tubular part 7 about one-half inch in diameter; and the pin 21 about five-sixteenths of an inch in diameter and the hook portion 6 about one-half inch in diameter. The hook 22 is preferably U shaped and open at the top; and the hook 25 U shaped and open at the side. While not necessary, it has also been found expedient to allow the upper end of the pin 21 to extend above the screw threaded portion 24 of the hook 25 so that it may cooperate with the hook 25 in anchoring the upper strand 26 of the line 1. The hook portion 6 in the present instance partakes of two loops in planes at right angles to one another, one loop 30 in a substantially horizontal plane, see Fig. 3, and the other loop 31 in a substantially vertical plane. The loop 30, in the present instance, is provided to enable the line 1 to clear the sash frame 10 when the arm 7 extends into the house, and the loop 31 extending upwardly from the loop 30 to receive the ear 13 of the pulley 5. In operation, the strand 26 of the line 1 may immediately be positioned in the hook 25 between it and the end 32 of the pin 21. When the arm 7 is swung into the house into the full line position shown in Figures 1, 2 and 3, the strand 27 is ready to receive the clothes, and both when hanging the clothes and removing the clothes from the strand 27 preferably the strand 27 extends down below the hook 22. After the clothes have been hung on the strand 27 of the line 1, the strand 27 is preferably adjusted so that all of the clothes are secured to the same between the pulley 2 and the hook 22. Thereupon the strand 27 should be raised and positioned in the hook 22, and thereupon the arm 7 is ready to be swung out of the house into the dotted line position shown in Fig. 2.

One of the features of the present invention resides in the fact that by this arrangement the arm 7 with the strands 26 and 27 disposed between the pulley 5 and the hooks 25 and 22 may be swung through the opening formed by the strands 26 and 27 between the pin 21 and the pulley 2.

Excellent results have been achieved with this

supporting device without providing anchoring means for securing the supporting device either in the position shown in Figure 1 where the arm 7 extends into the house, or in the position where the arm 7 extends along the outside of the house. This is due to the fact that the strain on the strands 26 and 27 when clothes are mounted thereon is deflected by the hooks 25 and 22 when the arm 7 forms an oblique angle with a straight line between the pulley 2 and the pin 21. Consequently, after the strands 26 and 27 are properly secured to the hooks 25 and 22, respectively, with or without clothes hanging on the strand 27, the arm 7 is free to be swung in a horizontal direction. However, in order to prevent accidental swinging of this arm 7 either due to a wind storm or the like, or even by an attendant, means are provided whereby the arm 7 can be anchored either in its outside position, see Fig. 4, or in its inside position, see Fig. 3. For anchoring the arm 7 in its outside position, the pivotally mounted plate 33, see particularly Figs. 7 and 8, is pivotally connected to the ear 34 bent at right angles to the web 28. This plate 33 has a projection 35 constituting a finger piece to raise the same, and a recess 36 to engage the plate 14. The edge 37 of the plate 33 serves as a cam when the plate 14 is swung toward the anchoring clip 33 to raise the clip 33 until the upper edge of the plate 14 registers with the recess 36 and permits the plate 33 to drop down into the position shown in Fig. 8, the edge 37 in this camming action, see Fig. 7, initially engaging the upper edge of the web 16 to raise the clip 33 as shown in Fig. 7. As shown in Fig. 6, the clip 33 has a nose 38 which rests against the web 28 when the clip 33 is free as shown in said Fig. 6. This locking clip 33 therefore acts as a latch automatically to lock the plate 14 into the position shown in Fig. 4. On the other hand, when it is desired to swing the arm 7 into the room, it is necessary first to raise the latch 33 to free the plate portion 15, and then to swing the arm 7 with its pulley 5 through the strands 26 and 27 about the hinge pin 21 until the arm extends adjacent to the inner portion of the frame sash 10 as shown in Fig. 3. For anchoring the arm 7, when extending into the house as shown in Fig. 3, it has been found desirable to provide a lever controlled bolt. The bolt consists of a shank 39, see Fig. 6, having a diminished portion 39 extending through the plate portion 15, with a collar portion 40 of the shank 39 to one side of the plate portion 15, and the washer 41 on the diminished portion 39 engage the other side of the plate portion 15. On the outer end of the diminished portion 39 there is formed a suitable lock nut 42 between which and the washer 41 there is secured the lever 43 fixed to rotate with the shank 39. The lever 43 has the finger piece 44. The tubular portion of the arm 7, see Fig. 6, extends beyond the faces of the plate portion 15 sufficiently to form limiting stops for the lever 43 when swung in either direction.

The shank 39 is also provided with an arrow shaped head 45 having the wings 46 and 47 diametrically opposed to one another and disposed just beyond the collar formation 48. The collar formation 48 has a greater diameter than the diameter of the opening 49 in the web or plate 20, which opening 49, however, is provided with two diametrically opposed recesses 50 and 51, see Fig. 5, to clear the wings 46 and 47 when registering therewith and enabling the arrow shaped head 45 to pass through the opening 49. Such passage

of the arrow head 45 will be permitted when the lever 43 is raised or in substantially erect position. Thereupon in order to anchor the plate portion 15 to the web 20 it will only be necessary to swing the lever 43 down when the wings 46 and 47 will clear the recesses 50 and 51 to sandwich the web 20 between the wings 46 and 47 on one side and the collar formation 48 on the other side. The collar formation 48 limits the inward swing of the arm 7 when extending into the house as shown in Fig. 3.

The angle between the web 16 and the plate portion 15 is preferably about 86° so that when the arm 7 is anchored on the outside of the house, the hook 31 and associated pulley 5 will be spaced from the outer face of the house as shown in Fig. 4, and in turn when the arm 7 is anchored to extend into the house, the hook portion 6 will clear the sash frame 10 as shown in Fig. 3.

As aforesaid, the hook elements 25 and 22 on the pin 21 rotate freely relative to the journals formed by the loops 17, 18 and 19, and consequently when the strands 26 and 27 are secured in such hook elements 25 and 22, they will freely move with the arm 7 at one time extending substantially at right angles to the web 20, see Fig. 3, when the arm 7 extends into the house, and at another time extending at an oblique angle to the web 20 of about 135°, see the position shown in Fig. 4, when the arm 7 extends adjacent to the outside of the house. It will be noted that when the arm 7 extends adjacent to the outside of the house that the upper strand 26 will form a loop around the hook portion 25. A similar loop will also be formed by the strand 27 around the lower hook element 22 when the arm 7 is disposed adjacent to the outside of the house.

It is obvious that various changes and modifications may be made to the details of construction without departing from the general spirit of the invention as set forth in the appended claims.

I claim:

1. A clothes line supporting device for the opening, such as a window or doorway of a house having a frame defining said opening, in combination with an endless clothes line, two pulleys, each supporting one end of said endless line, an exterior support supporting one of said pulleys, said device including a claw supporting the other pulley, a bent plate having one web secured to the outside of a house and its other web extending outwardly therefrom clear of said frame, a second plate hingedly mounted on the outwardly extending web of said bent plate clear of said frame, an arm on said second plate, said claw being formed on the free end of said arm, a guide at the upper end of said second plate for the upper strand of said line, a second guide at the lower end of said second plate for the lower strand of said line, said guides being spaced from one another sufficiently to enable said arm with its pulley and a portion of the clothes line to move between portions of the two strands to and from a position on the outside of the house and from and to a position inside of the house and substantially in alignment with the hinged connection between said second plate and said outwardly extending web, and an anchor pivotally mounted on said

bent plate and having a recess for receiving an edge of said second plate and for securing said second plate in position on the outside of the house.

5. A clothes line supporting device for the opening, such as a window or doorway of a house having a frame defining said opening, in combination with an endless clothes line, two pulleys, each supporting one end of said endless line, an exterior support supporting one of said pulleys, said device including a claw supporting the other pulley, a bent plate having one web secured to the outside of a house and its other web extending outwardly therefrom clear of said frame, a second plate hingedly mounted on the outwardly extending web of said first plate clear of said frame, an arm on said second plate, said claw being formed on the free end of said arm, a guide at the upper end of said second plate for the upper strand of said line, a second guide at the lower end of said second plate for the lower strand of said line, said guides being spaced from one another sufficiently to enable said arm with its pulley and a portion of the clothes line to move between portions of the two strands to and from a position on the outside of the house and from and to a position inside of the house, an anchor pivotally mounted on said bent plate and having a recess for receiving an edge of said second plate and for securing said second plate in position on the outside of the house, said outwardly extending web having an opening, and a stud on said second plate movable into the opening in said outwardly extending web and engaging the edge defining the opening in said outwardly extending web to secure said second plate in position when extending into the house.

3. A clothes line supporting device for the opening, such as a window or doorway of a house having a frame defining said opening, in combination with an endless clothes line, two pulleys, each supporting one end of said endless line, an exterior support supporting one of said pulleys, said device including a claw supporting the other pulley, a bent plate having one web secured to the outside of a house and its other web extending outwardly therefrom clear of said frame, a second plate, a hinge including a pin hingedly connecting said second plate to said outwardly extending web clear of said frame, an arm on said second plate, said claw being formed on the free end of said arm, a guiding claw at the upper end of said pin for engaging and guiding the upper strand of said line, a second guiding claw at the lower end of said pin for engaging and guiding the lower strand of said line, said guiding claws being spaced from one another sufficiently to enable said arm with its pulley and a portion of the clothes line to move between portions of the two strands to and from a position on the outside of the house and from and to a position inside of the house, and a latch pivotally mounted on the first web of said bent plate and having a recess for receiving the edge of said second plate and engaging and securing said second plate in position on the outside of the house.

ALEXANDER NAGY.
